UNITED STATES PATENT OFFICE.

FRED LONGTHORNE, OF UNDERCLIFFE, NEAR BRADFORD, ENGLAND, ASSIGNOR OF
ONE-HALF TO G. H. LEATHER LIMITED, OF BRADFORD, ENGLAND.

PROCESS OF PRODUCING INTERMITTENTLY-DYED YARN.

1,311,131.

Specification of Letters Patent.

Patented July 22, 1919.

Application filed April 15, 1919. Serial No. 290,340.

To all whom it may concern:

Be it known that I, FRED LONGTHORNE, subject of the King of Great Britain, residing at Undercliffe, near Bradford, in the county of York and Kingdom of England, have invented certain new and useful Improvements in the Processes of Producing Intermittently-Dyed Yarn, of which the following is a specification.

10 The present invention relates to an improved process for coloring textile fiber.

The invention is particularly applicable to the coloring or dyeing of fiber when it is in the state of a combed sliver, with a view to 15 producing "mélange" and the like yarns.

It has been usual to produce these yarns by causing the sliver to pass to a rotating printing roller which compressed a lateral band of color upon the sliver at predetermined spaced distances along it. It has been found, however, that this has the disadvantage that the band of color so impressed is deeper at the point where the printing surface leaves the sliver than at other parts, 25 giving an irregular or non-uniform result.

By the arrangement of the present invention a band, spot, strip or the like of color is impressed upon a textile sliver before it has reached the stage of a twisted yarn by 30 a reciprocating action so that color is impressed evenly upon the whole sliver surface so impressed.

This invention is more particularly described with reference to the accompanying 35 drawing showing an arrangement of a gill box combined with a dabbing device according to the present invention in end elevation.

A sliver 1 passing from a gill box 2 is 40 conveyed to the dabbing device of the present invention by conveyers 17 and 18. It then passes over a roller 5 which is permanently in contact with a color distributing roller 6 partly immersed in a color trough 7. A roller 8 removes the excess of color from 45 the roller 5. The sliver 1 is brought into contact with the roller 5 from time to time according to a predetermined rule by a reciprocating plunger 9 mounted adjustably on a spindle 10 which is reciprocated from 50 a crank on the shaft of a gear wheel driven by gearing 12, 13, 14, 15, from a shaft 16 the apron 4 conveys the sliver to receiving carriage 19 mounted on rails 3.

In another arrangement a pad having an inked surface may be adapted to descend 55 from time to time upon the sliver as it passes under it, which pad may receive fresh supplies of color from an inking roller passing over its surface from time to time or in any other suitable manner.

Either the printing surface itself or the abutment member acting as a counter-surface, between which surfaces the fiber is temporarily held during printing, may be elastically mounted, either pneumatically or 65 on springs, in order to yield resiliently to the printing impression or blow.

It is obvious that one or more of such printing devices may be arranged either in series or in parallel to one another, acting 70 on the band of combed fiber, or one or more of said devices may be arranged to act on parallel bands of combed fiber, which may then move on to subsequent requisite processes to form mixed colored yarn.

I declare that what I claim is:—

1. A process of coloring textile fiber, comprising forming a combed sliver of the fiber, and applying color thereto intermittently by a reciprocating action.

2. A process of forming mélange yarn comprising forming a combed sliver of the fiber, applying color thereto intermittently by a reciprocating action, and subsequently twisting said sliver into a yarn.

3. A process of forming mélange yarn comprising forming a combed sliver of the fiber, applying spots of color thereto by a reciprocating action, and subsequently forming said sliver into a yarn.

4. A process of forming mélange yarn comprising forming a combed sliver of the fiber, moving the same continuously, applying spots of color thereto intermittently by a reciprocating action, and subsequently forming said sliver into a yarn.

In witness whereof, I have hereunto signed my name this 18th day of March 1919, in the presence of two subscribing witnesses.

FRED LONGTHORNE.
